UNITED STATES PATENT OFFICE

VICTOR ANDERSON, OF NORTH BERGEN, NEW JERSEY, ASSIGNOR TO ALFRED HOFMANN & CO., OF WEST NEW YORK, NEW JERSEY, A CORPORATION OF NEW JERSEY

AUTOMATIC STOP

Application filed November 14, 1927. Serial No. 233,185.

This invention relates to improvements in automatic stops and contemplates the provision of a device which will effectually prevent reverse movement of a rotating element, such as a shaft, when the normal movement of the same has been arrested.

My invention is directed particularly to a stop which will prevent reverse rotation or back-lash of the drive shaft of knitting machines, where such reverse rotation would result in damage to the thread and needles of the machine.

Devices of this character have heretofore been proposed and, while their action is generally instantaneous and practically absolute, it has been found that, because of the arrangement of the parts, a torsional strain is imparted to the shaft with the result that the shaft becomes twisted to such an extent that it is in danger of breaking.

It is therefore a primary object of this invention to provide a stop in which the parts are so arranged that the braking force will be instantaneously applied at two diametrically opposite points of the shaft, thereby relieving the shaft of any strain which otherwise would be imposed upon it and, at the same time, insuring more effective prevention of back-lash or reverse rotation.

It is a further object of the invention to provide a stop of this character with arbitrarily actuated means for rendering the mechanism inoperative so that the shaft may be rotated in reverse direction at will.

Other objects and advantages will in part be obvious and in part more fully brought out as the description of the invention proceeds.

In the accompanying drawings, I have illustrated an embodiment of the invention; but it is to be understood that the drawings are illustrative, merely, and are in no way to be construed as limiting the invention to the details of construction therein shown.

In these drawings:

Fig. 1 is a front view, showing the parts of my stop in the position they occupy when the shaft is rotating in the direction of the arrow on the shaft;

Fig. 2 is a side elevation;

Fig. 3 is a view similar to Fig. 1, but showing the parts in the position they occupy when the machine is at rest;

Fig. 4 is a section on line 4—4 of Fig. 1;

Fig. 5 is a fragmentary perspective view of the means for arbitrarily rendering the stop inoperative; and

Fig. 6 is an enlarged diagrammatic view illustrating, in full lines, the position of the parts as in Fig. 1, and, in dotted lines, their position as in Fig. 3, the amount of movement being greatly exaggerated.

Referring now to the drawings, the reference-numeral 1 indicates a shaft suitably supported in bearings, one of which is shown at 2. Mounted upon the shaft is a disk 3 provided with a hub or collar 4 through which passes a securing bolt 5 by means of which the disk is rigidly connected to the shaft. The disk is provided with a peripheral flange 6 which forms with the side of the disk an annular recess.

An attaching plate 7 is suitably supported on a stationary part of the machine and on this plate is pivoted a bracket 8, the pivot connection being formed by a bolt 9 preferably provided with a bushing 10. The upper end of the bracket 8 is provided with a yoke, the opening of which is large enough to permit of the free passage of the shaft 1 without contacting therewith.

An annular plate 11 is secured to the yoke-end of the bracket 8 as by screws 12. This plate is provided with a centrally disposed aperture 13 of diameter slightly greater than that of the shaft 1 so that the shaft may pass freely therethrough without contacting with the plate. The plate is so supported that it will be housed completely within the annular recess formed by the flange 6 and the side of the disk 3 and fits therein with a slight clearance.

The plate 11 is cut out as at 14, the cut extending inwardly from the periphery of the plate, and this cut-out forms with the flange 6 a pocket 15 of a width decreasing in a direction opposite to the direction of normal rotation of the shaft. In this pocket is a roller 16.

Pivoted on the bracket 8 is a hand-lever 17

100
95

provided with a pin 18 extending into the pocket. The purpose of the lever is to raise the roller 16 to the upper, or wider, end of the pocket when it is desired to rotate the shaft in reverse direction. The hand-lever is maintained by friction at any position to which it may be moved.

In operation, when the shaft is rotating in the direction of the arrow in Fig. 1, the roller 10 will remain at the upper, or wider, end of the pocket, as is well understood. This position is shown in full lines in Fig. 6. When the rotation of the shaft is arrested, the roller will drop by gravity to the lower, or narrower, end of the pocket. If there is now any tendency for the shaft to rotate in a reverse direction, the roller will be instantly wedged into the narrow end of the pocket and will be forced tightly against the flange 6 at the point A indicated in Figs. 3 and 6. At the same time, the plate 11 will, by reason of its pivotal mounting, swing slightly to the left thus contacting with the flange 6 at the point B indicated in Figs. 3 and 6.

25 It will now be seen that contact is made with the flange 6 of the disk 3 at two diametrically opposite points at the same instant, thus effecting a more positive locking of the shaft than in devices heretofore proposed. 30 It will also be clear that by this arrangement the shaft is relieved of any torsional strain which might otherwise be imparted to it.

As heretofore described, the stop may be rendered inoperative by moving the lever 17 to raise the roller into the wider end of the pocket whereupon the shaft may be rotated in reverse direction at will.

It is obvious that my invention is susceptible of embodiment in forms other than 40 that herein described without departing from the spirit and scope of the invention as defined in the following claims.

What I claim is:

1. In an automatic stop, the combination 45 of a rotatable shaft, a recessed disk rigidly secured thereto and having a peripheral flange, a movable plate supported within the recess of the disk and forming with the peripheral flange a pocket of decreasing width, and a roller within said pocket.

2. In an automatic stop, the combination 55 of a rotatable shaft, a disk rigidly secured thereto and having a peripheral flange, a pivotally mounted bracket provided with a plate having a cut-out portion forming with said flange a pocket of decreasing width, and a roller in said pocket.

3. In an automatic stop, the combination 60 of a rotatable shaft, a disk rigidly secured thereto and having a peripheral flange forming with the side of the disk an annular recess, a pivotally mounted bracket provided with an annular plate seating loosely in said 65 recess, said plate having a cut-out portion

forming with said flange a pocket of decreasing width, and a roller in said pocket.

4. In an automatic stop, the combination 70 of a rotatable shaft, a disk rigidly secured thereto and having a peripheral flange, an apertured movable plate supported within said flange and having a cut-out portion forming with flange a pocket of decreasing width, said shaft passing freely through the aperture in said plate, and a roller in said 75 pocket of diameter greater than the width of the pocket at one end, and less than the width of the pocket at the other end.

5. In an automatic stop, the combination 80 of a rotatable shaft, a disk rigidly secured thereto and having a peripheral flange, an apertured movable plate supported within said flange and having a cut-out portion forming with the flange a pocket of decreasing width, said shaft passing freely through the aperture in said plate, a roller in said 85 pocket of diameter greater than the width of the pocket at one end, and less than the width of the pocket at the other end, and means to maintain the roller in the wider end 90 of the pocket.

6. In an automatic stop, the combination 95 of a rotatable shaft, a disk rigidly secured thereto and having a peripheral flange, a pivotally mounted apertured plate supported within said flange and having a cut-out portion forming with the flange a pocket decreasing in width in a direction opposite to the direction of normal rotation of said shaft, and a roller in said pocket of diameter greater 100 than the width of the pocket at one end and less than the width of the pocket at the other end, the roller remaining in the wider end of the pocket during normal rotation of the shaft and being wedged into the narrower end of the 105 pocket upon reverse rotation of the shaft, thereby moving the pivoted plate into contact with the peripheral flange at a point diametrically opposite to the point of contact of the roller with said flange.

In testimony wherof I affix my signature.

VICTOR ANDERSON.
